UNITED STATES PATENT OFFICE.

ISAAC N. EABY AND PAUL M. EABY, OF LANCASTER, PENNSYLVANIA.

MAIL AND PACKAGE TYING DEVICE.

1,228,192.

Specification of Letters Patent.

Patented May 29, 1917.

Application filed February 3, 1917. Serial No. 146,368.

To all whom it may concern:

Be it known that we, ISAAC N. EABY and PAUL M. EABY, citizens of the United States, residing at Lancaster, in the county of Lancaster and State of Pennsylvania, have invented certain new and useful Improvements in Mail and Package Tying Devices; and we do hereby declare the following to be a full, clear, and exact description of the 10 invention, such as will enable others skilled in the art to which it appertains to make and use the same.

This invention relates to package tying devices of general use, but more particularly adapted for use in tying bundles of mail.

In the mail service these packages must be tied with great rapidity and they must be capable of being untied with equal ease. 20 And it is most essential that these package tying devices be constructed simply, inexpensively, and that they be capable of being handled with the greatest possible speed. Devices of this same general nature have 25 heretofore been proposed but have not been generally used, because they were found to be unsuited for such service, in that they necessitated an extra motion, or permitted the operator's fingers to obstruct the cord 30 tying movement, or did not provide an adequate holding surface for the operator's hand, nor securely hold the package and did not afford a quick cord releasing movement.

The principal object of this invention is 35 to provide a package or mail tie so constructed that packages may be quickly and securely tied and may with equal speed be untied without cutting or destroying the flexible cord.

Another object of this invention is to construct a package tie formed with a holding means at a particular part thereof and so situated in respect to the cord securing means that the device may be securely held 40 in place while permitting a free and unobstructed tying movement.

Another object of this invention is to so locate the cord guide and the holding jaw on the fastening member that the device 45 naturally adapts itself to the universal cord tying motion which is used in the mail service.

Another object of this invention is to locate the cord guide and the holding means 50 so that when the package is tied, the cord enwinds the latter at its median sides, and the fastening member is prevented from canting and loosening the package.

Another object is to construct a simple, inexpensive device of few parts and easily 60 made.

A further feature of this invention is the relative disposition of the guide means, the thumb hold, the attaching means for the cord, and the final holding clip, so that the 65 speedy universal tying movement is possible. Another feature resides in the angular disposition of the guide to the holding member, permitting the cord to rest on the entire face of the guide and to be held through- 70 out the full length of the holding jaws.

Still other and further objects of this invention will in part be obvious and will in part be pointed out in the specification hereinafter following and by reference to the 75 accompanying drawings, in which—

Figure 1 represents a plan view showing the application of the tying device to a package of letters and illustrating the initial stage of the universal way of tying letters 80 as used in the postal service;

Fig. 2 represents the same, showing the completed movement;

Fig. 3 is a plan view of the fastener; and Fig. 4 is a longitudinal section of the fas- 85 tener.

The improved fastening member consists of a substantially flat plate 1, of any suitable material, but preferably of sheet metal or metal of sufficient thickness to afford the 90 requisite stiffness, having a broadened, heel-shaped holding end 2, preferably provided with a roughened surface 3. At the opposite end, the plate is provided with a narrowed toe 4 formed at an angle to the thumb-piece to facilitate the desired movement and provided with a cord securing member, which in the form shown consists of a spring gripping jaw 5, which, when the plate is made of metal, can be formed by bending 95 back the toe blank as shown in Fig. 4. Located approximately in the center of the plate and separated from the thumb-piece is the guide member 6, preferably formed by slitting the plate and bending upward the 100 end of such slitted portion in the form of a lip or projection 7. This member differs from the jaw 5, in that the former merely guides the cord whereas the latter functions as a positive holding member. Substantially 105 midway between the guide 6 and the jaw 5 and to the left of both, the plate is provided

110

with an ear 8, having a hole therethrough to which the cord may be attached. Obviously any manner of attaching the cord to the plate will suffice, it only being necessary that 5 the same be located in the prescribed relation to the guide and to the holding jaw.

It will be noted that the guiding face of the member 6 is arranged at an acute angle to the holding face of the jaw 5, which permits the cord to engage each of these individual members, uninterrupted and unobstructed by the other, thus allowing greater speed in the tying movement, and it also allows the cord to contact across the entire 15 face of the guide 6 and the jaw 5, thus insuring a more secure fastening.

By reference to Fig. 4, it will be seen that when the cord is drawn into the spring jaw 5, it will be held securely by a wedging action and that when it is desired to release the cord it is merely necessary to free the cord from the gripping jaws. In using this device the package is held in the left hand, the short side of the letter at the top, the plate 20 lying diagonally, as shown in Fig. 1, and the thumb of the left hand resting on the roughened heel, holding the plate firmly against the package and facing the operator; the cord is passed up and over the top, rearwardly and down the back of the packet, then forwardly and upwardly to the guide 25 6, across the same to the left, as shown in Fig. 1. From this position the cord is carried around and across the back of the bundle to the right and hence to the final gripping jaw 5, as shown in Fig. 2, finishing the tie with a movement away from the operator's body. Finally, if desired the free 30 end of the cord may be pulled downwardly 40 which gives the plate a slight tilting movement, tightening the cord and also wedging it more firmly between the jaws 5. Obviously, if it be desired, the cord may be carried a number of times around the package 45 before passing between the jaws 5. And this extra wrapping is permitted by the liberal space between the guide 6 and the jaws 5 and also by the angular disposition of these members.

50 The above manner of passing a cord around a packet of mail is the same as is

used in the postal service and is known as the "universal movement," and this device is particularly adapted for this exact motion, its construction allowing the operator's 55 thumb to tightly hold the plate and at the same time to be out of the way of the cord when it passes across the packet.

Having thus described our invention, what we claim as new and desire to secure by Letters Patent of the United States is:

1. A mail or package tying device consisting of a substantially flat, oblong plate provided at one end with a thumb-piece, a cord guide independent thereof and separated 65 therefrom, said guide being integral with the plate and projecting upwardly therefrom, cord holding means formed at the opposite end of the plate, and cord attaching means located at one side of said plate and 70 intermediate of said guide and holding means.

2. A mail or package tying device consisting of a substantially flat, oblong plate broadened at one end to provide a thumb-piece and at the other end having a slightly offset toe portion provided with cord gripping means, said plate being slotted intermediate its ends to provide an integral, upwardly-projecting guide tongue and a cord 80 attaching means located between the guide and cord gripping means and laterally thereof.

3. An article of manufacture consisting of an oblong plate of sheet metal of single 85 thickness throughout, having an enlarged end roughened on its upper surface to provide a holding face, and being slotted adjacent thereto to form an integral guide tongue projecting above the surface of the plate, the 90 opposite end of the plate being folded back to provide a spring holding jaw, said plate being also provided with a cord attaching means located between said guide and holding 95 means and laterally offset therefrom.

In testimony whereof we affix our signatures in the presence of two witnesses.
